UNITED STATES PATENT OFFICE.

FRANK J. VAN COTT, OF UNADILLA, NEW YORK.

SILO-REENFORCING STRUCTURE.

Application filed March 5, 1921. Serial No. 449,908.

To all whom it may concern:

Be it known that I, FRANK J. VAN COTT, a citizen of the United States, and a resident of Unadilla, in the county of Otsego 5 and State of New York, have invented a certain new and useful Silo-reenforcing Structure, of which the following is a specification.

The object of my invention is to provide 10 a reenforcing structure for silos, which is of simple, durable and inexpensive construction, and can readily and easily be installed on any silo.

More particularly my invention relates 15 to a reenforcing structure for circular buildings, which when installed may be adjusted or moved to position where the wall of the circular building will retain a true circle in form, the parts being so arranged that 20 the upper end of the silo or circular building will be rigidly braced against movement in any direction whatsoever.

Another object is to provide inclined 25 rafters which are fixed to the upper end of the circular wall, the upper ends of the rafters being held together, and members placed between the lower ends of the rafters, for holding them at proper spaced intervals. The lower ends of the rafters are con- 30 nected together by an adjustable tension device. The tension device and upper ends of the rafters being connected together so that an inward exertion may be applied to the wall at the lower ends of the rafters.

Still another object is to provide spacing 35 members which are fixed to the upper end of a silo wall and adapted to have their ends abut against each other, and means for exerting an inward pull on the silo wall, the 40 spacing members preventing movement of the silo wall at the points where they engage the silo wall, thus fixing several points of the silo wall in a true circle.

Still another object is to provide spacing 45 members which are fixed to the upper end of a silo wall and adapted to have their ends abut against each other, and means for exerting an inward pull on the silo wall, the spacing members preventing movement 50 of the silo wall at the points where they engage the silo wall, thus fixing several points of the silo wall in a true circle, and filler blocks curved from end to end fixed to the spacing members for preventing an

inward movement of the silo wall between 55 the ends of the spacing members.

Still another object is to provide holder devices adapted to support the ends of the spacing members and to receive the lower ends of the inclined rafters, thus fixing the 60 rafters and spacing members against movement relative to each other, and a centering device spaced equidistant from the ends of the rafters and connected to the holder devices by rods, the rods being provided 65 with screw threaded portions whereby adjustment may be had for pulling the holder devices towards the center.

Still another object is to provide on the outer side of the holder devices hook por- 70 tions adapted to receive the upper end of the anchoring cable.

Still another object is to provide inclined 75 rafters held together at their upper ends by a member having a peripheral flange under which is extended the roof boards, spacing members arranged to rest between the ends of the rafters and filler blocks, fixed to the spacing members and adapted to have one edge rest against the inner surface of the 80 silo wall for preventing the inward movement of the silo wall and help it retain its circular form, and a hoop extended around the outside of the silo wall for preventing expansion or outward movement of the silo 85 wall.

With these and other objects in view, my invention consists in the construction arrangement and combination of the various parts of my device, whereby the objects contemplated are attained, as hereinafter more fully set forth, pointed out in my claims, and illustrated in the accompanying drawings, in which:

Figure 1 is a central, vertical, sectional 95 view taken through my improved roof structure.

Figure 2 is a horizontal, sectional view taken on the line 2—2 of Figure 1.

Figure 3 is a detail, sectional view taken 100 on the line 3—3 of Figure 1, showing how the rafters and roof boards are held together at their upper ends.

Figure 4 is a sectional view taken on the line 4—4 of Figure 2, showing how the spac- 105 ing members are held in position.

Figure 5 is a sectional view taken on the line 5—5 of Figure 2.

Figure 6 is a perspective view of the holder device which holds the spacing members and the rafters together.

Figure 7 is a central, sectional view taken 5 on the line 7—7 of Figure 2.

Figure 8 is a top or plan view of a modified form of my reenforcing device.

Figure 9 is a perspective view of the holder 10 used in connection with the form of my device shown in Figure 8.

Figure 10 is another form of my reenforcing device; and

Figure 11 is a central, sectional view, taken 15 on line 11—11 of Figure 10.

10 In the accompanying drawings I have used the reference numeral 10 to indicate generally a circular wall which may be of wooden staves or any other suitable material. In the drawings I have shown the 20 circular walls as made up of wooden staves.

The upper end of the wall 10 is bevelled as at 11. Inclined rafters 12 are provided which have their lower ends abutting against the wall 10.

25 In order to hold the rafters together at their upper ends I have provided a member 13 which is provided with a series of sockets 14 in which are received the ends of the rafters 12. The sockets 14 hold the upper 30 ends of the rafters in proper spaced relationship to each other.

A peripheral flange 15 is provided on the member 13. Roof boards 16 have their upper ends placed below the flange 15, and 35 have their upper ends abutting against the member 13.

The lower ends of the roof boards 16 are 40 fixed to the bevelled surface 11 of the wall 10, and have their lower ends projected out beyond the sides of the wall 10.

The member 13 is provided with a central opening 17 through which is extended a rod 18 having the screw threaded ends 19. Nuts 20 are provided on the screw threaded ends 45 19. The purposes of the rod 18 will be hereafter more fully set forth.

Hoops 21 are placed around the outside of the wall 10 for preventing expansion thereof.

50 Holder devices A are placed over the upper edge of the wall 10. The upper end of the wall 10, at the place where the holder device A is placed thereover, is provided with a horizontal upper edge instead of the bevelled edge as illustrated in Figure 4 of the drawings.

Each of the holder devices A is provided with an outer side member 22 and an inner side member 23. The silo wall 10 is received 60 between the inner and outer side members 23 and 22.

The upper ends of the side members 22 and 23 are connected together by a plate 24.

65 It will be seen that a substantially yoke shaped portion is formed by the sides 22, 23

and the plate 24. The plate 24 is provided with an opening 25, as illustrated in Figure 6 of the drawings, the purpose of which will be hereafter fully set forth.

Extending inwardly from the side 23 are 70 the socket members 26 which are spaced relative to each other.

The sides of the socket member 26 are provided with registering openings 27. The sides 22 and 23 are also provided with 75 registering openings 28.

The holder devices A are placed over the upper end of the silo wall 10 and the inclined rafters 12 have a portion of their lower end received in the opening 25 and 80 the balance of their lower ends abutted or rested against the inner side of the silo wall and in between the spaced sockets 26.

It will be seen that the adjacent edges of plate 24 will prevent sideward movement of 85 the lower end of the rafter 12. The lower end of the rafter 12 may be bolted or nailed to the upper edge of the wall 10.

In order to properly space the lower end 90 of the rafters and prevent any movement of the rafters or holder device A, I have provided spacing members 29 which have their ends received in and supported by the socket members 26.

The ends of the spacing members 29 abut 95 against the rafters 12, as illustrated in Figures 1 and 2 of the drawings.

A bolt 30 may be extended through the openings 27 in the sockets 26 and through the spacing member 29 for holding the ends 100 of the spacing members in position and against any possible movement.

From the construction just described it will be seen that I have provided rafters which are fixed to the silo wall and have 105 their lower ends properly spaced apart and held in that position against any possible movement.

The spacing members 29 form chords relative to the circle of the silo wall. The upper edge of the members 29 are curved from 110 end to end as at 31, as illustrated in Figure 1 of the drawings.

The curving of the upper edge of the members 29 makes it possible to have the 115 edge 31 rest against the roof boards 16 at all points. The roof boards 16 may be also nailed to the spacing members 29.

The outer side 22 of the holder device A is provided with a hook portion 32 which 120 receives the upper end of the anchoring cable 33. A clamp 34 on the cable 33 locks the cable to the hook 32.

By anchoring the upper end of the cable 33 to the holder device A it will be seen that 125 I have provided a place to anchor the upper end of the cable which will be rigid and very effective.

A centering member B spaced equidistant 130 from the ends of the rafters is provided

which has a bottom 35 and an upwardly extending flange 36.

The flange 36 is provided with a plurality of openings through which are extended the 5 inner ends of the rods 37 which extend radially outwardly from the centering device B.

The inner ends of the rods 37 are screw threaded as at 38 for receiving nuts 39. The 10 nuts 39 are received on the end of the rod 37 which is within the centering device B.

The outer ends of the rods 37 extend through the registering openings 28 in the side 22 and 23 of the holder device A, and 15 through a corresponding opening 40 in the silo wall 10.

The outer end of the rods 37 are also screw threaded as at 41 and receive the nuts 42.

It will be seen that by tightening the nuts 20 42 or 39 on the rods 37 that the silo wall may be pulled inwardly or towards the centering device B.

An opening 43 in the bottom 35 of the centering device B permits the lower end 25 of the rod 18 to extend therethrough.

When the rods 37 have been tightened then the screwing of the nuts 20 on the rod 18 will cause the centering device and the member 13 to be drawn towards each other and 30 held in their drawn position.

The drawing of the member 13 and the centering device towards each other tends to cause the lower ends of the rafters 12 to be moved outwardly and downwardly, while 35 the centering device B and the rods 37 tend to pull the silo wall inwardly, thus forming a very rigid construction and insuring the silo wall at the points where the rafters engage the wall against any movement whatsoever.

In order to prevent any inward movement of the wall 10 between the end of the rafters I have provided filler blocks 44 which are curved from end to end on their outer 45 edge so as to conform to the inner surface of the circular wall 10.

The filler blocks 44 are fixed to the lower edge of the spacing members 29 by any suitable means.

50 The silo wall 10 may be nailed to the filler blocks 44.

By the use of the filler blocks 44 I am positively assured of no inward movement of the wall 10 between the lower ends of the 55 rafters 12, thus giving me a means of reinforcing the inner surface of the silo wall against any undesired inward movement and also making it possible to have the silo retain its true form.

60 It will be understood that in many cases when silos are blown down it is due to the silo becoming oval shaped rather than circular; the result of the silo becoming oval shaped causes a portion of the staves to leave 65 their position in the circle, thus making it

possible for the silo to be easily blown over. With my device the retaining of the silo wall in a true circle at all times eliminates the danger of having the silo wall or a portion thereof leave its position in the circle.

70

The anchoring of the cable to the holder device A and to a point where the rafters, spaced members and the centering device meet is an advantage, because when pressure is applied to one side of the silo it is equally 75 distributed by means of my roof structure, so that to a great extent pressure at one point on the wall is substantially eliminated.

In Figures 8 and 9 I have shown a slightly modified form of device in which I use a 80 holder device C which comprises socket portions 45 and the yoke portion 46. The yoke portion 46 is designed to extend over the upper edge of the circular wall 10.

Spacing members 47 are provided which 85 are similar to the spacing members 29 and have their ends received in the sockets 45. The ends of the spacing members 47 abut against each other.

An opening 48 is provided between the 90 sockets 45 and in the yoke 46. The rods 37 of the centering device extend through the registering openings 48, and through the openings formed in the wall 1, and the ends of the spacing members 47.

95

Filler blocks 44 are fixed to the spacing members 47 and hold the wall 10 against inward movement between the holder devices C.

In this form of device it will be seen that 100 when the centering device B is tightened that it will cause the ends of the spacing members 47 to abut against each other and form a brace against any inward undesired movement.

105

In Figures 10 and 11 I have shown the filler blocks 44 serving as the spacing members for holding the wall rigid and against movement. The filler blocks 44 have their ends 50 abutting against each other so as to 110 form a wedge against inward movement of the wall which rests against their outer curved edge.

In order to prevent outward movement of the parts I have provided a member 51 similar in construction to the filler blocks 44. The members 51 are placed against the underside of the filler blocks. The members 51 are staggered relative to the filler blocks so that the abutting ends of the filler blocks 120 come at the point where the strength of the member 51 is greatest.

Bolts 52 extend through the filler blocks and members 51 for holding them together. In order to further brace the filler blocks 125 and members 51 I employ a saddle device 53 which is S-shaped in cross section.

The saddle device has one of its endslapping over the abutting ends of the filler blocks and thence under them and over the 130

center of the members 51 and terminates on the underside of the member 51.

A bolt 54 connects the ends of the saddle device 53 so as to prevent movement thereof relative to the filler blocks or members 51.

The advantages of my device are that I am able to completely reinforce the silo wall against inward undesired movement and to provide such a roof structure that will act as a reinforcing means for preventing the inward movement of the wall.

My device is simple and can readily and easily be installed and the holder device forms a means for holding the parts together and in proper position relative to each other, while the rafters and spacing members are being installed and permanently locked.

My device can at any time be adjusted for tightening the various parts and for always holding the wall 10 in its true form, that is, a circle.

It will be understood that the silo wall expands and contracts, due to the swelling and shrinking of the staves. With my device it will not in any way seriously interfere with the wall 10 and cause it to become loosened from its form, because I am able to tighten the outside hoop and then adjust my improved device which will lock and hold the silo in its true form.

It will be understood that where I have used the term silo wall, that I do not intend to be limited to silo walls or silos, as my improved structure may be used for any circular wall building.

Some changes may be made in the construction and arrangement of the details of my device without departing from the real spirit and purpose of my invention, and it is my intention to cover by my claims, any modified forms of structure or use of mechanical equivalents, which may be reasonably included within their scope.

I claim as my invention:

1. The combination of a silo wall with a roof structure comprising a series of inclined rafters, means for supporting and connecting the upper ends of said rafters, means positioned within and centered with relation to the silo wall for preventing distortion of the silo wall, means for drawing said first and last means together, and means for preventing inward movement of the silo wall, said last means including filler members arranged to have their ends abut against each other and have one of their sides rest against the inner surface of the silo wall.

2. The combination of a silo wall with a roof structure, comprising a series of inclined rafters, means for supporting and connecting the upper ends of said rafters, means positioned within and centered with relation to the silo wall for preventing distortion of the silo wall, means for drawing

said first and last means together, means for spacing the lower ends of said rafters from each other, and means for preventing inward movement of the silo wall, said last means including filler members arranged to have their ends abut against each other and have one of their sides rest against the inner surface of the silo wall.

3. The combination of a silo wall with a roof structure, comprising a central member having sockets, a series of rafters received in said sockets and inclined downwardly and outwardly therefrom to the silo wall, a member positioned within and centered with relation to the silo wall for preventing distortion of the silo wall, means for drawing said first member and said last member together for forcing said first member downwardly into snug engagement with said rafters, and means for preventing inward movement of the silo wall, said last means including filler members arranged to have their ends abut against each other, and have one of their sides rest against the inner surface of the silo wall.

4. The combination of a silo wall with a roof structure, comprising a series of inclined rafters, means for supporting and connecting the upper ends of said rafters, means arranged concentric with the lower ends of said rafters and connected with the lower ends of said rafters, for preventing movement of the lower ends of said rafters, means for drawing said first and last means together, and means for spacing the lower ends of said rafters from each other, the units of said last means being arranged on chords of the circle formed by the silo wall, and filler members arranged between the units of said last means and the silo wall.

5. The combination of a circular silo wall with a roof structure, comprising a series of inclined rafters arranged to abut against the inner surface of the silo wall at their lower ends, a member for connecting and supporting the upper ends of said rafters, a member positioned within and centered with relation to the silo wall for preventing distortion of the silo wall, means for drawing said members together, and means for preventing inward movement of the silo wall, said last means including filler members arranged to have their ends abut against each other and have one of their sides rest against the inner surface of the silo wall.

6. The combination of a circular silo wall with a roof structure, comprising a series of inclined rafters arranged to abut against the inner surface of the silo wall at their lower ends, a member for connecting and supporting the upper ends of said rafters, a member for connecting the lower ends of said rafters together, and means for drawing said members together, cross members for

spacing the lower ends of the rafters apart arranged on the chords of the circle of the silo, and filler members arranged between said cross members and the silo wall for preventing its inward movement between the rafters.

7. The combination of a circular silo wall with a roof structure, comprising a series of inclined rafters arranged to abut against the inner surface of the silo wall at their lower ends, a member for connecting and supporting the upper ends of said rafters, a member positioned within and centered with relation to the silo wall for preventing distortion of the silo wall, and means for drawing said members together, cross members for spacing the lower ends of the rafters apart arranged on chords of the circle of the silo, filler members extending from said cross members to the inner surface of the silo wall for preventing any inward movement of the silo wall.

8. In a device of the class described, the combination of a circular silo wall with a roof structure, comprising a series of inclined rafters, a member for connecting and supporting the upper ends of said rafters, means for exerting an inward pull on the silo wall and the lower ends of the rafters and a downward pull on said member, and means for preventing inward movement of the silo wall between the points of operation of said last means, said last means including filler members having one of their sides resting against the inner surface of the silo wall.

9. In a device of the class described, the combination of a circular silo wall with a roof structure, comprising a series of inclined rafters, a member for connecting and supporting the upper ends of said rafters, and a downward pull on said member, members for holding the lower ends of said rafters properly spaced, and filler members adapted to coact with said last members for preventing the inward movement of the silo wall between the rafters.

10. In a device of the class described, the combination of a circular silo wall with a roof structure, comprising a series of inclined rafters, a member for connecting and supporting the upper ends of said rafters, and means for exerting an inward pull on the silo wall and the lower ends of the rafters and a downward pull on said member, means for holding the lower ends of said rafters properly spaced, and means for preventing inward movement of the portions of

60 the silo wall between the lower ends of the respective rafters, said last means including filler members having one of their sides resting against the inner surface of the silo wall.

11. The combination of a circular silo wall with a roof structure, comprising a series

of inclined rafters arranged to abut against the inner surface of the silo wall at their lower ends, a member for connecting and supporting the upper ends of said rafters, a member positioned within and centered with relation to the silo wall for preventing distortion of the silo wall, means for drawing said members together, and means for preventing inward movement of the silo wall between the rafters, said last means including filler members arranged to have their ends abut and have one of their sides against the inner surface of the silo wall.

12. In a device of the class described, the combination of a circular silo wall with a roof structure, comprising a series of inclined rafters, a member for connecting and supporting the upper ends of said rafters, and means for exerting an inward pull on the silo wall and the lower ends of the rafters and a downward pull on said member, means for holding the lower ends of said rafters properly spaced, means for preventing inward movement of the portions of the silo walls between the lower ends of the respective rafters, said last means including filler members having one of their sides resting against the inner surface of the silo wall, and means for preventing expansion of the silo wall.

13. In a device of the class described, the combination of a circular silo wall and a hoop for preventing the expansion of said wall with a roof structure comprising a series of inclined rafters, a central member having sockets for receiving and supporting the upper ends of said rafters, said rafters being arranged to abut against the inner surface of the silo wall, means for holding the lower ends of said rafters in spaced position, a member positioned within and centered with relation to the silo wall for preventing distortion of the silo wall, means for connecting said member with the silo wall, an adjustable device for connecting said first and last members with each other for drawing them toward each other, and filler members curved from end to end designed to rest against the inner surface of the silo wall for preventing its inward movement.

14. The combination of a circular silo wall with a roof structure, comprising a series of inclined rafters arranged to abut against the inner surface of the silo wall at their lower ends, a member for connecting and supporting the upper ends of said rafters a member positioned within and centered with relation to the silo wall for preventing distortion of the silo wall, and means for drawing said members together, cross members for spacing the lower ends of the rafters apart arranged on chords of the circle of the silo, and filler members curved from end to end to conform to the circle of the silo wall, arranged between said cross members and

the silo wall for preventing its inward movement between the rafters.

15. In a device of the class described, the combination of a circular silo wall, and means for preventing expansion of said silo wall with a roof structure comprising a plurality of inclined rafters, a member for supporting and engaging the upper ends of said rafters, means for simultaneously drawing the member downwardly and the lower ends of said rafters inwardly, and filler members curved from end to end adapted to rest against the inner surface of the silo wall for preventing inward movement thereof.

16. In a device of the class described, the combination of a circular silo wall, and means for preventing expansion of said wall with a roof structure comprising a plurality of inclined rafters, a member for supporting and engaging the upper ends of said rafters, means for simultaneously drawing the member downwardly and the lower ends of said rafters inwardly, and means for holding the lower ends of said rafters in spaced relation, and means for preventing inward movement of the silo wall between the respective rafters, said last means including members curved from end to end and adapted to rest against the inner surface of the silo wall.

17. In a device of the class described, the combination of a circular silo wall, and means for preventing expansion of said wall with a roof structure comprising a plurality of inclined rafters, a member for supporting and engaging the upper ends of said rafters, means for simultaneously drawing the member downwardly and the lower ends of said rafters inwardly, means for holding the lower ends of said rafters in spaced relation, said last means being curved from end to end, and silo roof members resting on said rafters and on said curved surfaces of said last members.

18. In a device of the class described, a means for supporting and connecting the upper ends of inclined rafters of a silo roof, comprising a body having a plurality of sockets therein arranged to receive and support the upper ends of said rafters, members arranged to space the lower ends of said rafters, and roof boards placed on said rafters, said body having at its outer upper portion a peripheral flange spaced above said sockets and adapted to receive the upper ends of said roof boards therein.

19. In a device of the class described, the combination of a circular wall and means for preventing expansion of said wall, members arranged to rest against the wall and have their ends abut against each other, a holder device fixed to the wall and adapted to receive the ends of said members for supporting them, a centering device

equidistant from the ends of said members, rods connected to said centering device and holder device whereby the wall may be pulled inwardly by adjustment of said rods and held outwardly by said first members.

20. In a device of the class described, the combination of a circular wall and means for preventing expansion of said wall, members arranged to rest against the wall and have their ends abut against each other, filler blocks curved from end to end fixed to said members, and means for drawing the ends of members inwardly, said filler blocks preventing inward movement of the wall between the ends of said members.

21. In a device of the class described, the combination of a circular wall and means for preventing expansion of said wall, members arranged to rest against the wall and have their ends abut against each other, a holder device fixed to the wall and adapted to receive the ends of said members for supporting them, said holder device including a yoke adapted to extend over the edge of the wall and provided with sockets on its inner side for receiving the ends of said members, and means for drawing the ends of said members inwardly.

22. In a device of the class described, the combination of a circular wall and means for preventing expansion of said wall, members arranged to rest against the wall and have their ends abut against each other, a holder device fixed to the wall and adapted to receive the ends of said members for supporting them, said holder device including a yoke adapted to extend over the edge of the wall and provided with sockets on its inner side and a hook on its outer side for receiving the end of an anchoring cable.

23. In a device of the class described, the combination of a circular silo wall with a roof structure, comprising a series of inclined rafters, a member for connecting and supporting the upper ends of said rafters, and means for exerting an inward pull on the silo wall and the lower ends of the rafters and a downward pull on said member, and a holder device for supporting the ends of said rafters, said holder device being supported on the upper edge of the silo wall.

24. In a device of the class described, the combination of a circular silo wall with a roof structure, comprising a series of inclined rafters, a member for connecting and supporting the upper ends of said rafters, and means for exerting an inward pull on the silo wall and the lower ends of said rafters and a downward pull on said member, means for holding the lower ends of said rafters properly spaced and preventing inward movement of the portions of the silo wall between the lower ends of the respective rafters, and a holder device for support-

ing the ends of said rafters and the ends of said last members for preventing movement of them relative to each other.

25. In a device of the class described, the 5 combination of a circular wall and means for preventing expansion of said wall, members arranged to rest against the wall and have their ends abut against each other for preventing inward movement of the wall, 10 and a means secured to the silo wall for preventing outward movement of the last members at their adjacent ends, whereby the circular wall will retain its true form.

26. In a device of the class described, the 15 combination of a circular wall and means for preventing expansion of said wall, members arranged to rest against the wall and have their ends abut against each other for preventing inward movement of the wall, 20 and a means for preventing outward movement of the last members at their adjacent ends, whereby the circular wall will retain its true form, said last means including members fixed to the first members.

25. 27. In a device of the class described, the combination of a circular wall and means for preventing expansion of said wall, members arranged to rest against the wall and have their ends abut against each other for 30 preventing inward movement of the wall, and a means for preventing outward movement of the last members at their adjacent ends, whereby the circular wall will retain its true form, said last means including 35 members fixed to said first members, and a saddle device for holding the ends of said first members to the last member.

28. In a device of the class described, the 40 combination of a circular wall and means for preventing expansion of said wall, members arranged to rest against the wall and have their ends abut against each other for preventing inward movement of the wall, and a means for preventing outward move- 45 ment of the last members at their adjacent

ends, whereby the circular wall will retain its true form, said members having one edge curved from end to end, so as to conform to the curvature of the wall.

29. In a device of the class described, the 50 combination of a circular silo wall with a roof structure, comprising a series of inclined rafters connected together at their upper ends and resting upon the silo wall at their lower ends, whereby the rafters will 55 be supported in proper position, means for exerting an inward pull on the silo wall at various points, and means for preventing inward movement of the silo wall between the points of operation of said last means 60 for normally retaining the silo in its true circular form.

30. In a device of the class described, the 65 combination of a circular silo wall with a roof structure, comprising a series of inclined rafters, a member for connecting and supporting the upper ends of said rafters, means for exerting an inward pull on the silo wall and the lower ends of the rafters, and means for preventing inward move- 70 ment of the silo wall between the points of operation of said last means, said last means including filler members having one of their sides resting against the inner surface of the silo wall.

31. In a device of the class described, the 75 combination of a circular silo wall with a roof structure, comprising a series of inclined rafters connected together at their upper ends and resting upon the silo 80 wall at their lower ends, whereby the rafters will be supported in proper position, means for exerting an inward pull on the silo at the lower ends of said rafters, and means for preventing inward pull of the silo wall 85 between the points of operation of said last means for normally retaining the silo in its true circular form.

Des Moines, Iowa, October 11, 1920.

FRANK J. VAN COTT.
